UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed March 26, 1927. Serial No. 178,557.

This invention relates to signaling systems and more particularly to machine switching telephone exchange systems and has for an object the provision of improved means for establishing telephonic connections between offices employing different types of switching equipment.

It is well known that automatic switches of the panel type are operated by associating the switches with continuously moving rollers or similar driving apparatus and that the position assumed by such switches is controlled by means of impulses sent from the switch to a control device or sender. Automatic switches of the step-by-step type are directly operated by means of a magnet or magnets, the circuit of which is controlled by impulses normally transmitted from the subscriber's substation. Where offices employing both types of switches exist in the same exchange area, the interconnection of such offices requires that the equipment be capable of adaptation to control the particular type of apparatus to which the connection is to be extended.

In accordance with the present invention the control device at an office employing power driven switches is characterized in this that it is equipped with means for receiving pulses from power driven switches and for transmitting pulses to step-by-step switches; that means are provided for determining the number of impulses in each case and the control device discriminates between these means in accordance with the designation of the called office; that the impulse transmitting means has a plurality of normal positions and the number determining means is preferably so associated therewith as to have the same numerical significance irrespective of the normal position from which this impulse transmitting means starts; and that a timing arrangement is provided which is effective where a call is extended to step-by-step switches to allow for the trunk hunting operation by these switches and this timing means is so arranged that the duration of the interval measured may be varied at will.

The invention finds embodiment in a reg-

ister sender forming a part of a power driven system. The initiation of a call by a subscriber causes the association of a calling line with a district selector and through a sender selector with a sender. The operation of the subscriber's dial results in the registration of the number of the wanted subscriber in the sender. In response to the dialing of the digits forming the code of the office in which the called subscriber is located, the code registers are positioned and a translator is set therefrom to control the selection of an outgoing trunk to that office. The translator positions a class switch, which controls the operation of the sender in accordance with the nature of that office. In the establishment of a connection to an outgoing trunk, reverte impulses over a fundamental circuit are employed under the control of counting relays, the number to be operated being determined by the translator. Since these operations take place within the calling office they are the same for all classes of distant offices. Where the called office also employs power driven switches, the further establishment of the connection is controlled by reverte impulses and the counting relays are successively operated over one element of each numerical register of the sender. Where the distant office is one employing step-by-step switches, the class switch will be so positioned as to transfer the fundamental circuit from the control of the counting relays to a sequence switch type impulse transmitter. It likewise renders a different element of each register effective to control a counting arrangement associated with the interrupting device. This impulse transmitting sequence switch has a plurality of normal positions and is operated over the contacts of a relay which when released permits the switch to pass by a normal position and when operated causes the switch to stop in the next normal position. This relay is operated over multiple connections to the registers, which are rendered successively effective, to close a shunt around the impulsive contact when it has operated the proper number of times. The circuit of this relay is altered each time that

the impulsing sequence switch comes to rest in order that the multiple connections to the registers may appear in the same numerical order irrespective of the normal position from which the impulsing switch is started. When the impulsing switch comes to rest, a timing sequence switch is operated to measure a time interval during which the step-by-step switches hunt for an idle trunk. 10 This timing sequence switch causes the transfer of the control from register to register and prepares for the transmission of the next set of impulses. It is provided with a plurality of sets of contacts, any one 15 of which sets may be employed so that the time interval may be varied at will.

The scope of the invention will be more clearly understood from a consideration of the following detailed description and 20 claims in connection with the accompanying drawings in which:

Fig. 1 shows a calling subscriber's substation together with a diagrammatic showing of a district selector and an office selector at the calling office and the necessary power driven switches and step-by-step switches for completing the connection to a subscriber in either type of office. A portion of a register sender is also shown;

Fig. 2 shows the control circuit of a register sender including the counting relays;

Fig. 3 shows a class switch of the sender, and the relay call indicator impulser indicated by the dotted rectangle at the right 25 side of the figure;

Fig. 4 shows the impulse transmitting sequence switch and timing switch embodying features of the invention;

Fig. 5 shows the code registers and register control switch of the sender;

Fig. 6 shows the translator and numerical registers of the sender; and

Fig. 7 shows the manner in which Figs. 1 and 6 are to be arranged.

The parts of the sender embodying the present invention have been disclosed in detail but only so much of the remaining parts have been shown as are believed necessary to an understanding thereof. A complete disclosure of a sender to which the present invention is applicable may be found in U. S. Patent 1,589,402 to O. H. Kopp granted June 22, 1926. This patent also discloses a district selector in detail and reference is made thereto for a complete disclosure of those portions of a system disclosed only fragmentarily herein. It may be noted that the translator shown in Fig. 6 in practice consists of two switches which are operated simultaneously and that each switch has two sets of brushes and double terminal banks. Likewise it is customary to employ two sets of compensating resistances but since these features do not enter into 60 the present invention they have been sim-

plified in the manner shown. The operation of step-by-step switches is well known but reference may be made to U. S. Patent 1,231,013 granted to C. L. Goodrum June 26, 1917, for a detailed showing thereof.

Call to power driven office.

Assuming that the subscriber at substation 100 wishes to converse with the subscriber at substation 101 who is served by power driven machine switching apparatus and whose number is Booth 2579, he will remove his receiver from the switchhook and this operation will cause the association of his line with a district selector and a register sender in any desired manner, for example, as disclosed in the above mentioned patent to O. H. Kopp. Switch 190 represents the link circuit of that disclosure. When the idle sender has been selected a dialing circuit is established from battery through the winding of relay 102, link 190, lower right and upper left contacts of sequence switch cam 103, through line finder 104 to substation 100, back through the line finder 104, left contacts of cam 105 to ground through the right winding of coil 106. The establishment of this circuit causes the transmission of tone from coil 123 to the substation 100 to inform the subscriber that the sender is ready to receive dial impulses. Other circuits not shown are completed for holding the sender busy and for connecting ground to the upper left contact of cam 201 and thence to the winding of sequence switch magnet 200, driving that sequence switch to position 2 in which position certain off-normal circuits are closed. These operations are fully described in the above mentioned patent to O. H. Kopp.

The operation of relay 102 closes an obvious circuit for relay 107 which in turn closes a circuit for relay 108. When now the subscriber operates his dial to transmit the first letter of the office code, namely B, having a digital equivalent of 2, relay 102 releases. Since relay 107 is slow to release it remains operated and a circuit is closed from ground over the back contact of relay 102, inner right front contact of relay 108, conductor 109, winding of relay 530, brush 501 of register control switch 500 in normal position, winding of stepping magnet 515, right back contact of relay 531 to battery. Relay 530 and magnet 515 operate in this circuit. The operation of relay 530 closes a circuit from ground over the left front contact of relay 108, conductor 532, front contact of relay 530, winding of magnet 506 to battery. Magnet 506 attracts its armature but since relay 530 is slow-to-release does not step the register control switch 500 until the digit has been completed. Magnet 515 in operating attracts its armature and at the completion of the first pulse releases it to

step register 510 to its first off-normal position. A branch of the circuit of magnet 515 extends over the back contact of that magnet, conductor 507, brush 502 in normal position, left contact of relay 531, conductor 111 to the winding of relay 110 and battery. This relay operates, connecting ground to conductor 109 and to the winding of relay 107 until magnet 515 operates, to render the 5 operation of the register magnet independent of the duration of the dial pulse. A similar circuit is closed over brush 502 for the setting of each register. The circuit of relay 102 is interrupted twice and switch 510 advances to its second off-normal position. 10

Following the transmission of the first digit relay 102 remains operated long enough to permit relay 530 to release. Magnet 506 now retracts its armature to step the register 15 control switch to its first off-normal position. The pulsing circuit now extends over the first off-normal contact of brush 501, left back contact of relay 533, winding of magnet 525 and thence to battery. Switch 520 is now advanced under control of the dial to 20 its sixth off-normal position and control switch 500 is advanced to its second off-normal position in response to the dialing of the second code letter.

25 As soon as this occurs a circuit is closed from battery through the winding of relay 534, normal contact of relay 534, second off-normal terminal of brush 503, conductor 535, outer right front contact of relay 108 to ground at the upper left contact of cam 203. Relay 534 closes a circuit from battery through the winding of translator operating magnet 647, back contact of magnet 646, to ground at the outer right front contact of 30 relay 534. Relay 534 also closes a circuit from grounded conductor 535, left contact of relay 534, brush 512 and its second off-normal terminal, brush 523 and its sixth off-normal terminal, conductor 536 to terminal 35 650 associated with brush 641 of the translator. The translator is rotated under the control of magnet 647 in search of this marked contact. When brush 641 encounters terminal 650, the above traced circuit is completed over brush 641, conductor 651 to the winding of relay 537 and battery and in parallel therewith to the winding of magnet 646 and battery. Magnet 646 opens the circuit of magnet 647 and also applies a brake 40 to bring translator switch 640 to rest in the position marked. Relay 537 closes a locking circuit for relay 534 extending from battery, winding of relay 534 and its inner right front contact, contact of cam 204, outer left 45 contact of relay 537 to ground. Relay 537 locks over its inner right contact to ground at the outer right front contact of relay 534. It closes a circuit from ground over its inner left front contact, lower left contact of cam 51, winding of sequence switch magnet 250

to battery to advance this sequence switch to position 2. It also closes a circuit from ground over its middle right front contact, lower left contact of cam 201 to the winding of sequence magnet 200 to advance that sequence switch to position 3. It further closes a circuit from ground over its outer right front contact brush 645, terminal 652, contact of cross-connecting rack 301, lower right contact of cam 315, winding of class 70 sequence switch magnet 300 to battery to move sequence switch 300 to one of positions 7 or 18 in which positions the sender is prepared to control the establishment of a connection by means of power driven switches. 75

80 At the same time, the numerical registers 600, 610, 620 and 630 are being positioned and control switch 500 advanced in accordance with the dialing of the remaining digits. Thousands register 600 is set on its second off-normal terminals, hundreds register 610 on its fifth, tens register 620 on its seventh, and units register 630 on its ninth off-normal terminals. Switch 500 stops in its sixth off-normal position when dialing is 85 completed.

90 With sequence switch 200 in position 3 and sequence switch 250 in position 2 a fundamental circuit is established for controlling district brush selection. This circuit may be traced in part from the upper right contact of district selector sequence switch cam 121, to which the district relay is connected, over conductor 112, through link 190, outer left normal contact of relay 113, right back contact of relay 114, right contact of cam 205, right contacts of cam 252, winding of stepping relay 253, left winding of relay 254, back contact of relay 255, resistance 206, lower contact of cam 207 to ground at the lower contact of cam 256. Relay 253 operates in this circuit but relay 254 is polarized so as not to operate at this time. The operation of relay 253 closes a circuit from ground over the upper right contact of cam 256, front contact of relay 253, lower right contact of cam 260, right normal contact of relay 352, right contact of cam 209, lower contact of cam 259, lower right contact of cam 258, brush 644 of the 100 translator, conductor 257, back contact of the No. 1' counting relay, winding of the No. 1 counting relay, contact of cam 208 to battery. The No. 1 counting relay operates and locks through the winding of the No. 1' 105 counting relay to ground at the left contact of cam 274, but the No. 1' relay does not operate being shunted by the operating circuit of the No. 1 relay. Stepping relay 253 is released in the well known manner by the 110 advance of the district selector and relay No. 1' operates to extend conductor 257 to the winding of the No. 0 counting relay which is operated and locked when relay 253 115 reoperates. The second release of relay 253 120

permits the operation of relays 261 and 255 in the locking circuit of the No. 0 counting relay. The operation of relay 255 opens the fundamental circuit to advance the district selector to position for group selection. The operation of relay 261 closes a circuit from ground over its front contact, lower right contact of cam 210, lower right contact of cam 251 to the winding of sequence switch 10 magnet 250 and battery, advancing the sequence switch to position 4, and releasing the operated counting relays.

In position 4 the fundamental circuit is established as before. A similar counting relay circuit is established this time over the left contact of cam 258 and brush 643. Following the completion of group selection, sequence switch 250 is advanced to position 6 in the same manner as it was advanced to 20 position 4. The district selector is caused to hunt for an idle office selector and the district selector sequence switch then comes to rest in a position where the fundamental circuit is extended over the brushes of the 25 district selector to the office selector.

A circuit is now established for testing the condition of the office selector which may be traced from the office selector over the tip brush of the district selector, right contacts of cam 121 and thence, as previously traced, to the right contact of cam 205, through resistance 263, upper right contact of cam 264, winding of relay 265, winding of relay 253, left winding of relay 254, back 30 contact of relay 255, upper left contact of cam 266, lower left and upper right contacts of cam 211, conductor 212, brush 642, through a portion of compensating resistance 648, conductor 649, contacts of cam 213, left back 35 contact of relay 115, inner left normal contact of relay 113, through the link 190, conductor 116, lower left and upper right contacts of cam 122, ring brush of the district selector to ground in the office selector. If 40 the office selector is ready to make selections, relay 265 operates, in turn operating relay 267. When relay 267 operates a circuit is closed from battery, through winding of sequence switch magnet 250, over the lower left contact of cam 262, left front contact of relay 267 to ground at the lower left contact of cam 203. Sequence switch 250 is advanced to position 7 and immediately out of position 7 to position 8 over the upper 45 left contact of cam 251. In position 8 the fundamental circuit for office brush selection is closed. This extends as traced for office test with the exception that a shunt is closed over the right contacts of cam 252 around 50 resistance 263 and relay 265. The counting relay circuits for this selection and office group selection extend through brushes of the translator but these have not been shown. Sequence switch 250 is advanced to position 55 10 following office brush selection and to

position 12 following office group selection.

In position 12 the trunk extending to the incoming selector is tested over the same circuit in the sender as that to the office selector. Sequence switch 250 is advanced to position 14 if the selector is ready. The fundamental circuit in position 14 is the same as previously traced except that it extends to battery and ground in the incoming selector. The counting relay circuit extends, as previously traced, to the lower left contact of cam 259, and thence over the upper right contact of cam 259, left normal contact of relay 350, brush 602 of the thousands register 600 in its second off-normal 60 position, conductor 257 to the back contact of the No. 1' counting relay, winding of the No. 1' counting relay to battery at the contact of cam 208. Incoming brush selection now takes place after which sequence switch 250 is advanced to position 16. The fundamental circuit for incoming group selection is the same as traced, the counting relay circuit extending at this time over the left contacts of cam 259, brush 601 of the thousands register in position 2, left front contact of relay 653 (which is operated since register 610 is in position 5) to the winding of the No. 3 counting relay. At the completion of this selection sequence 65 switch 250 is advanced to position 18.

With switch 250 in position 18 a circuit is closed from battery through the winding of sequence switch magnet 200, upper right contact of cam 201, contacts of cam 270, 100 right contact of cam 304 to ground, advancing sequence switch 200 to position 4. The fundamental circuit now extends over the lower left contact of cam 205, lower contacts of cam 252, to the windings of relay 253 and 105 relay 254, back contact of relay 255, upper right contact of cam 266, lower right and upper left contacts of cam 211, conductor 212 and thence as previously traced. In practice the circuit would be arranged so 110 that a different compensating resistance might be used for these selections. Final brush selection takes place with sequence switch 250 in position 18, final tens selection in position 2 and final units selection in 115 position 4 in the manner described, the counting relay circuit being completed over contacts of cam 277 and brushes 612, 622 and 632 respectively.

When the selections are completed sequence switch 250 is advanced to position 6 and a circuit is closed for relays 253 and 254. It will be noted that since switch 200 is in position 4 the circuit which formerly extended to relay 265 in position 6 is not 125 closed. When selections have been completed the incoming selector reverses the connection of battery to the fundamental circuit in the well known manner, causing the operation of polarized relay 254. This re- 130

lay locks in a circuit from battery through its right winding, contact of cam 271 to ground at its right front contact. In conjunction with relay 253 it closes a circuit 5 for the No. 0 counting relay. The incoming selector removes battery after a brief interval so that relay 253 releases to cause relays 255 and 261 to operate. The operation of relay 261 advances sequence switch 250 10 from position 6 whence it advances to position 8. Relay 254 releases during this advance.

Since relay 254 was operated at the time, the operation of relay 261 also closed a circuit 15 from ground at its front contact, lower left contact of cam 210, outer left contact of relay 254, to the windings of relays 114 and 115 in parallel. These relays operate, opening the fundamental circuit and causing 20 the advance of the district selector to a position in which it is ready for making talking selection. In addition the operation of relay 114 closes a locking circuit for relays 114 and 115 over its left front contact 25 to ground at the upper contact of cam 214. Relay 115 in operating closes a circuit from ground over its outer right front contact, left contact of cam 215, winding of sequence switch magnet 200 to battery, advancing the sequence switch to position 5.

The advance of the district selector opens the circuit for relay 102 which in turn releases relays 107 and 108. With relay 107 released a circuit is closed from ground at 35 its normal contact over conductor 539, brush 505, and its sixth, seventh and eighth off-normal terminals, back contact and winding of magnet 506 to battery. Switch 500 is advanced to its ninth off-normal position in 40 this circuit. When switch 500 arrives in this position the circuit for making talking selection is completed extending from the district selector over conductor 112, outer left normal contact of relay 113, right front 45 contact of relay 114, upper left and lower right contacts of cam 252, winding of relay 253, left winding of relay 254, back contact of relay 255, resistance 206, upper contact of cam 207, ninth terminal of brush 505, conductor 539 to ground at the normal contact of relay 107. The counting relay circuit for this selection is also completed through the translator but is not shown. Following the selection, the operation of relay 261 advances sequence switch 200 to position 55 6. As soon as the switch reaches position 6, a circuit is closed from battery, through the winding of magnet 250, the upper left contact of cam 251, lower right contact of cam 203 to ground to advance sequence switch 250 to position 1. Sequence switch 200 is then also advanced to position 60 7, which is also a normal position, over a circuit which extends over a normal contact of the relay call indicator impulser switch,

upper contacts of cam 269 to ground. The sender is now ready for another call.

Call to step-by-step office.

If the subscriber at substation 100 wishes 70 to converse with the subscriber at substation 191 located in the step-by-step office whose number may be assumed to be IN-wood 2579 he will dial the number of that subscriber in the same manner as for any 75 other office. Register 510 will be positioned on its fourth off-normal terminals and switch 520 on its sixth. The operation of relay 534 extends ground from conductor 535 over its left front contact, brush 512 80 and its fourth terminal, brush 522 and its sixth terminal to terminal 655 associated with brush 641. Translator 640 therefore comes to rest in the corresponding position. The operation of relay 537 closes a circuit 85 from ground over its outer right front contact, brush 645, contact 654, cross-connecting rack 301, lower left contact of cam 302, winding of class sequence switch magnet 300 to battery. Class switch 300 therefore 90 is moved to position 4 to control the establishment of the connection over step-by-step switches. The district and office selections are made as before except that a trunk is selected extending to the step-by-step office. 95 When sequence switch 250 reaches position 10½, following district and office selections, relays 350, 351, 352 and 353 are operated in parallel circuits extending from battery through their windings, right back contacts 100 of relay 118, contacts of cams 275 and 216, left contact of cam 304 to ground. This circuit is maintained until sequence switch 250 reaches position 9 on its second revolution. With relay 350 operated and switch 300 in 105 position 4 the counting relay circuits are opened, while the circuits which render the registers successively effective are transferred from brushes 602, 612, 622 and 632 to brushes 603, 613, 623 and 633, respectively, and from controlling the relay call indicator impulse switch to controlling the step-by-step impulse switch. Relays 351 an 352 restore the multiple connections from the thousands register to the same 110 numerical order as the other registers, the relay call indicator code for this digit differing from that for the hundreds digit, etc. Relay 352 also transfers the circuit controlled by the registers from the contact of 115 the stepping relay 253 to ground. Relay 353 opens certain connections to the relay call indicator impulse switch. Otherwise the selection of an outgoing trunk and the advance of sequence switch 250 to position 120 12 is the same as previously described.

With switch 250 in position 12 and switch 200 in position 3 the fundamental circuit including relay 265 is reestablished extending from battery through the upper winding 125

of relay 161, side switch arm 162 in position 1, terminal 163, tip brushes of the office selector and district selector, right contacts of cam 121, conductor 112, through the link 190, outer left normal contact of relay 113, right back contact of relay 114, right contact of cam 205, upper contact of cam 303, lower right contact of cam 264, winding of relay 265, winding of relay 253, left winding of relay 254, back contact of relay 255, lower contact of cam 266, conductor 212, brush 642, compensating resistance 648, conductor 649, contacts of cam 213, left back contact of relay 115, inner left normal contact of relay 113, through the link 190, conductor 116, lower left and upper right contacts of cam 122, ring brushes of the district selector and office selector, terminal 164, side switch arm 165, in position 1, lower winding of relay 161 to ground. It will be noted that resistance 263 is shunted at this time. Relays 161 and 265 both operate in this circuit. Relay 161 closes an obvious circuit for relay 166 which prepares the operating circuit of the first selector. Relay 265 operates relay 267 in the usual manner, advancing sequence switch 250 to position 14. Relays 161 and 265 are maintained operated in position 14 by means of a circuit which extends as traced to the upper contact of cam 303 and thence over the right front contact of relay 267, left contact of cam 264, to the winding of relay 265. In position 14 a circuit is closed from battery through the winding of relay 113, right contacts of cam 305, conductor 309, contacts of cam 273, right contact of cam 274 to ground. Relay 113 locks over its inner left front contact, outer left back contact of relay 118, right contact of cam 275, right contact of cam 216 to ground at the left contact of cam 304. Relay 113 in operating extends the circuit of relay 161 by means of its make-before-break contacts to the impulse sequence switch 400, the circuit now extending from battery through the upper winding of relay 161 and thence as traced to the outer left alternate contact of relay 113, conductor 117, lower contact of cam 401, back contact of relay 403, conductor 402, inner left alternate contact of relay 113 and back to ground through the lower winding of relay 161. The circuit of the relay 161 is therefore maintained during these changes at the sender.

The operation of relay 113 also initiates the transmission of pulses for operating the first selector by closing a circuit from battery through the winding of sequence switch magnet 400, left contact of cam 405, right back contact of relay 404, lower right contact of cam 451, conductor 452, outer right front contact of relay 113, inner left contact of relay 118, contact of cam 276 to ground. Sequence switch 400 will be

moved from its normal position 1 by this circuit. The pulsing circuit above described is maintained until switch 400 leaves position 1 $\frac{1}{4}$ over the lower contact of cam 401. In position 1 $\frac{3}{8}$ it is maintained over the upper contact of cam 401. The cam contacts having a fixed width, these circuits overlap and the pulsing circuit is not opened until switch 400 leaves position 1 $\frac{3}{8}$. With both contacts of cam 401 opened, which occurs as soon as the switch leaves position 1 $\frac{3}{8}$, the circuit of relay 161 is opened and that relay falls back to advance the first selector through one vertical step. In position 1 $\frac{1}{4}$ a circuit is closed from battery through the winding of relay 403, upper contact of cam 406, conductor 407, lower right and upper left contacts of cam 306, upper left contact of cam 203 to ground. Relay 403 locks over its right front contact, left back contact of relay 404 to grounded conductor 407. As switch 400 passes through position 2 $\frac{3}{8}$ the upper contact of cam 401 is again closed and relay 161 reoperates. When the switch leaves position 2 $\frac{3}{8}$ the pulsing circuit is opened a second time and relay 161 falls back to advance the first selector a second step. When sequence switch 400 reaches position 3 $\frac{3}{8}$ the upper contact is again closed, and relay 161 again operates. As soon as switch 400 reaches position 3 $\frac{1}{2}$ a circuit is closed from battery through the winding of relay 404, the left back contact of relay 412, outer left back contacts of relays 411 and 410, lower right contact of cam 420, conductor 442, the inner right front contact of relay 352, second off-normal terminal of thousands register brush 603, left contacts of cam 310, outer left alternate contact of relay 350, upper right and lower left contacts of cam 259, right contact of cam 209, outer right front contact of relay 352 to ground. Relay 404 operates in this circuit locking over its inner right contact, lower right contact of cam 453 to grounded conductor 407. Relay 404 in operating connects conductors 117 and 402 together over its outer right front contact independent of the contacts of cam 401, thus preventing the transmission of any more impulses. In addition it opens the locking circuit of relay 403 permitting this relay to release as soon as switch 400 reaches position 4. It also opens at its left back contact the operating circuit for magnet 400 so that this magnet comes to rest in its next normal position, namely, position 4.

The operation of relay 404 also initiates the operation of timing switch 450 to provide a time interval in which the first selector may hunt for an idle trunk, by closing a circuit from battery through the winding of relay 456, right back contact of relay 457, lower right contact of cam 458, inner

left front contact of relay 404 to grounded conductor 407. Relay 456 closes an obvious circuit for relay 457 and locks over its inner right front contact to grounded conductor 452. Relay 457 in operating closes a circuit from battery through the winding of sequence switch magnet 450, lower right contact of cam 459, inner left front contact of relay 457 to ground, advancing sequence switch 450 from position 1. With sequence switch 450 in position 2 a circuit is closed from battery through the winding and normal contact of relay 410, upper contact of cam 409, lower contact of cam 454, inner left front contact of relay 404 to grounded conductor 407. Relay 410 locks over its right alternate contact, lower right contact of cam 461, to grounded conductor 407 as soon as sequence switch reaches position 3. Switch 450 is advanced through position 2 by means of ground connected to the lower right contact of cam 460. Relay 456 in operating also closes a circuit from ground at its left front contact, lower contacts of cam 311, upper right contact of cam 262, winding of magnet 250 to battery, advancing sequence switch 250 to position 18 passing directly through position 16 in which incoming group selection was made under the joint control of the thousands and hundreds registers in extending the previously traced call. As switch 250 leaves position 17 the locking circuit of relay 456 is opened and that relay releases in turn opening the circuit of relay 457. When relay 456 releases the operating circuit of magnet 250 is opened thus insuring that sequence switch 250 will not be driven beyond position 18. With sequence switch 250 in position 18, sequence switch 200 is advanced to position 4 as previously described. Relay 457 has an individual locking circuit extending over its right front contacts and right back contacts of relays 410, 411 and 412 to the lower contact of cam 413 which is maintained until one of these relays is operated. Since switch 400 came to rest in position 4, relay 410 operated as soon as switch 450 moved from position 1 so that relay 457 is released at this time. With both relays 456 and 457 released a circuit is closed from battery through the winding of magnet 450, lower right contact of cam 455, left back contacts of relays 456 and 457 to ground at the upper right contact of cam 413. Sequence switch 450 is advanced to position 4 in this circuit. As switch 450 passes from position 3 to position 4 the locking circuit of relay 404 is opened and that relay releases. However, with relay 403 released the shunt around the pulsing contact of cam 401 is maintained closed. When relay 404 closes its back contact sequence switch 400 is advanced from position 4 over the circuit traced in position 1. As it passes from position 4 $\frac{3}{4}$ the circuit of the pulsing relay of the second selector is opened to advance that selector one vertical step. Relay 403 operates as soon as switch 400 reaches position 4 $\frac{3}{4}$. Since hundreds register 610 is in position 5, conductor 445 is grounded, the circuit extending from brush 613 over the lower left and upper right contacts of cam 312, inner right front contact of relay 350, upper right and lower left contacts of cam 277, left contact of cam 209, to ground at the outer right contact of relay 352. Since relay 410 is operated the circuit from conductor 445 over the lower left contact of cam 421 is open and relay 404 is not operated in position 6 $\frac{1}{2}$. Therefore when switch 400 reaches position 7 its start circuit remains closed and it continues to advance from position 7. When it reaches position 9 $\frac{1}{2}$ the grounded conductor 445 is extended over the lower left contact of cam 424, outer left front contact of relay 410, outer left back contacts of relays 411 and 412 to the winding of relay 404. Relay 404 performs the same functions as previously described so that only 5 impulses are sent out and switch 400 comes to rest in position 10. Relays 456 and 457 are operated, relay 456 advancing sequence switch 250 from position 18 to position 2, and relay 457 advancing the sequence switch 450 from position 4. Switch 450 is carried through position 5 as it was carried through position 2. When sequence switch 450 leaves position 4, the locking circuit of relay 410 is opened and that relay releases. With sequence switch 400 in position 10, and switch 450 in position 5, relay 412 is operated over the lower right contact of cam 409. Relays 456 and 457 are released as before, and switch 450 is advanced to position 7. The cycle of operations above described is now repeated to cause the transmission of seven impulses to direct the connector switch to its seventh level. Register 620 being in position 7, ground is connected to conductor 447, over brush 623, lower left and upper right contacts of cam 313, inner left front contact of relay 350, lower contacts of cam 277, left contact of cam 209 to ground at the outer right contact of relay 352. With relay 412 operated the multiple connections from conductor 447 over cams 421, 424 and 427 are opened. When sequence switch 400 reaches position 17 $\frac{1}{2}$, conductor 447 is extended over the upper right contact of cam 430, inner left back contact of relay 410, inner left back contact of relay 411, left front contact of relay 412 to the winding of relay 404, to stop the transmission of pulses and to bring sequence switch 400 to rest in position 1. Sequence 450 is advanced from position 7 to position 8 by the operation of relay 404, releasing relay 412. Since the connector performs no trunk hunting operation, the time interval need be only long enough to

transfer from vertical to rotary operation. Therefore switch 450 is moved through no intermediate positions, but relays 457 and 456 are operated at once in position 8. Relay 456 advances sequence switch 250 to position 4. Since sequence switch 400 came to rest in position 1, none of the relays 410, 411 or 412 are operated, but no locking circuit is provided for relay 457 with switch 400 in position 1, therefore relay 457 releases when relay 456 releases due to the advance of sequence switch 250. The release of these relays advances switch 450 to position 9 in which position it causes the reoperation of sequence switch 400 to transmit impulses to cause the connector to advance to the terminals of the wanted line. With units register 630 in position 9, conductor 449 is grounded over brush 633, lower left and upper right contacts of cam 314, outer right alternate contact of relay 350, left contacts of cam 277, left contact of cam 209 and the outer right alternate contact of relay 352. Since none of the relays 410, 411 or 412 is operated, the multiple connection of conductor 449 to the lower contact of cam 422 is effective to operate relay 404 following the transmission of nine impulses, arresting sequence switch 400 in position 13. As before, relay 404 causes the operation of relays 456 and 457. Relay 456 advances sequence switch 250 to position 6 and relay 457 advances sequence switch 450 to position 10. A locking circuit for relay 404 is closed over the right front contact of that relay, lower contact of cam 406 to grounded conductor 407 until switch 400 leaves position 12½, but no locking circuit is closed over cam 453. Therefore, relay 404 is released when switch 400 comes to rest in position 13. However, since switch 450 is in position 10 the operating circuit of magnet 400 is open at cam 451 and the sequence switch remains at rest. The pulsing circuit remains closed over the lower contact of cam 401 and the back contact of relay 403.

With sequence switch 450 in position 10, a circuit is closed from battery through the windings of relays 114 and 115 in parallel, lower left and upper right contacts of cam 268, conductor 278, lower right contact of cam 462 to ground. Relay 114 closes the same locking circuit for itself and relay 115 as when operated in the previous case. Relay 115 causes the advance of sequence switch 200 to position 5 as previously described. It also serves to advance sequence switch 250 to position 8 over the lower right contact of cam 262, in place of the reversal of battery supplied by the power driven incoming selector. As before, the operation of these relays causes the district selector to advance to position for talking selection, at which time the connector is held from the district selector.

The advance of the district releases relays 65 102, 107 and 108, causing register control switch 500 to advance to its ninth off-normal position. Since class sequence switch 300 is in position 4, the release of relay 108 also closes a circuit from battery through the 70 winding of relay 118, conductor 119, contacts of cam 308, right back contact of relay 108 to ground at the upper right contact of cam 203. This relay opens the holding circuit of relay 113 restoring the fundamental circuit. The release of relay 108 also closes a circuit from ground at its left normal contact, conductor 463, upper contact of cam 464, winding of sequence switch magnet 450 to battery advancing this sequence switch to position 1. When sequence switch 450 reaches position 1, conductor 463 is extended over the lower contact of cam 464, right contact of cam 405, winding of sequence switch magnet 400 to battery, advancing sequence switch 400 to position 1. 80 85

As soon as the fundamental circuit is restored, talking selection takes place, and sequence switch 200 is advanced to position 6. 90

With sequence switch 200 in position 6, sequence switch 250 is moved to position 1 and the sender restored to normal as before.

As a further illustration of the manner in which the pulsing sequence switch 400 operates, assume that the wanted number is 5525. The sequence switch 400 will be started from position 1 as previously described. Since the first digit is 5, conductor 445 will be grounded from brush 603 of the thousands register. Pulses will be sent out from cam 401 as described in passing from positions 13½, 23½, 33½, 43½ and 53½. In position 6½ grounded conductor 445 will be connected over the lower left contact of cam 421 and the back contacts of relays 410, 411 and 412 100 105 to the winding of relay 404 which in operating shunts the pulsing contact 401 and performs the other functions heretofore described in detail, bringing switch 400 to rest in position 7. The advance of the timing sequence switch 450 closes a circuit from battery through the winding and normal contact of relay 411, lower right contact of cam 409, lower contact of cam 454, left front contact of relay 404, to grounded conductor 407, relay 411 locking over the lower right contact of cam 461 to grounded conductor 407. 110

When switch 400 again starts to rotate conductor 445 is again grounded, this time from brush 613 of the hundreds register. With relay 411 operated the multiple connection of conductor 445 over cam 421 which was formerly effective is open as is also that over cam 424. Sequence switch 400 therefore continues to rotate until it reaches position 12½ having caused the transmission of 5 impulses. In position 12½ conductor 120 125

- 445 is connected over the lower left contact of cam 427, outer left front contact of relay 411, back contact of relay 412 to the winding of relay 404. With relay 404 operated 5 switch 400 stops in position 13. Switch 450 is now again operated releasing relay 411 and closing circuits from battery through the winding and normal contact of relay 410 over the upper cam of contact 409 10 and from battery through the winding and normal contact of relay 412, over the left contact of cam 409, and thence as previously traced to grounded conductor 407 to which both relays lock.
- 15 After the measured time interval, switch 400 is advanced from position 13. Tens register 620 is now effective to ground conductor 442 over brush 623. Conductor 442 is connected in multiple to the lower right contacts of cams 420, 423, 426, 429, 432, and 20 435. With both relays 410 and 412 operated it will be seen that the only one of these connections which is effective is that over cam 432. After two pulses have been sent 25 out switch 400 reaches position 15½ and relay 404 is operated over cam 432. Switch 400 is then brought to rest in position 16. The advance of timing switch 450 releases relays 410 and 412 but in the next position 30 of that switch relays 411 and 412 are operated over the lower contacts of cam 409.
- Units register 630 is effective on the next advance of sequence switch 400 to ground conductor 445. With relays 411 and 412 operated only the multiple connection from conductor 445 to the lower left contact of cam 436 is effective. As sequence switch 400 passes through positions 16¾, 17¾, 18¾, 35 1¾ and 2¾, five pulses are sent out from cam 401. In position 3½ relay 404 is operated and the transmission of pulses ceases, switch 400 stopping in position 4. It is believed that this description in connection with the more complete description previously given will clearly indicate how the multiple connections from the registers become 45 ineffective in the same numerical order, irrespective of the normal position from which sequence switch 400 advances.
- 50 The function of sequence switch 450 as above indicated is to introduce a time interval between series of impulses during which the step-by-step switches may perform their trunk hunting operation. In order that this 55 time interval may be adjustable in accordance with the needs of the office in which the sender of the invention is being installed, a plurality of sets of circuits have been provided. The circuits performing the same 60 functions are terminated on cross-connecting racks and are so arranged that when the incoming conductors are connected to the contacts occupying the same relative position on the corresponding racks they will 65 operate to function as described above, in which case the lowermost contact on each rack was employed. Were the second contact on each rack used, the switch 450 would be moved from position 1 to position 5 during the trunk hunting operation of the first 70 selector and from position 5 to position 9 during the trunk hunting operation of the second selector. In the case of the third contacts switch 450 would be moved from position 1 to position 7 during trunk hunting 75 by the first selector and in the case of the fourth or top contacts, from position 1 to position 9 at this time. Similar intervals are provided for the second selector while the same interval is allowed for the transfer 80 from vertical selection to rotary selection by the connector switch in each case.
- Call to operator.*
- This sender is also provided with means 85 whereby a special four digit code may be used for making calls to operators, etc., permitting a greater variety of such calls than is provided by the usual 1-1-X or X-1-1 type of code. The codes which may be employed in connection with the present arrangement lie between 1001 and 1019, inclusive. When register 510 is advanced one step in response to the dialing of the digit 1, and relay 530 releases, a circuit is closed 90 from battery through the left winding of relay 531, first off-normal terminal of brush 511, contacts of cam 217, normal contact of relay 530, conductor 532 to ground at the inner left front contact of relay 108. Magnet 506 of the register control switch 500 is held operated in a circuit from battery through the winding of the magnet, brush 513 in its first off-normal position, conductor 95 535, outer right front contact of relay 108, to ground at the upper contact of cam 203. Thus magnet 506 cannot release to advance the register control switch to its first off-normal position. Relay 531 opens the operating circuit of magnet 515 and also closes 100 a holding circuit for itself from battery through its right winding and inner right front contact, normal contact of brush 501, to the winding of relay 530. When relay 530 is operated in response to the dialing 105 of the next digit, the operating circuit of relay 531 is opened. Since relay 102 attracts its armature following the first impulse, the holding circuit of relay 531 is also opened so that it restores the circuit of magnet 515 and the remaining digits are received 110 on register 510. Since the second digit is 0, a circuit is closed when register 510 comes to rest from battery through the winding of relay 533, brush 511 in position 10, contacts 115 of cam 217, normal contact of relay 530, conductor 532 to ground at the left front contact of relay 108. Relay 533 extends its operating circuit over its inner right front contact, terminal 10 of brush 513 to the wind- 120 125 130

ing of magnet 506 again preventing the release of this magnet to advance the control circuits to register 520. In addition it transfers the operating circuit from the first off-
 5 normal terminal of brush 501 from magnet 525 of the code register 520 to magnet 634 of the units numerical register. It likewise transfers the circuit of relay 110 from the back contact of magnet 525 to the back contact
 10 of magnet 634. When the next digit is received, it is registered on the second half of the register 510. This digit will be either zero or 1, neither one of which is employed in the usual office code, so that terminals 11
 15 and 20 associated with brush 512 are connected to brush 631 of register 630. Following this digit magnet 506 is permitted to release to advance switch 500. Due to the operated condition of relay 533, the 4th digit
 20 is registered on the units register 630, and the combined setting of register 510 and register 630 is employed to set the translator. It will be observed that the digit 1 was absorbed in the usual manner. The manner of
 25 employing the second half of the first code register has been employed heretofore, to afford an opportunity for enlarging the number of office codes, as described and claimed in U. S. Patent 1,595,072 granted August 10,
 30 1926, to H. C. Caverly.

What is claimed is:

1. In a telephone exchange system, a switch controlling mechanism comprising registers having a plurality of elements, means for controlling the setting of switches of one type by impulses received from said switches during the setting thereof under the control of certain elements of said registers, means for controlling the setting of switches of another type by transmitting impulses thereto under the control of other elements of said registers, means dependent upon the office designation of a call for selecting either of said switch controlling means, and means controlled by said last means to select the proper elements of said registers.
2. In a telephone exchange system, a switch controlling mechanism comprising registers having a plurality of brushes and terminal banks, means for controlling the setting of switches of one type by impulses received from said switches during the setting thereof under the control of certain brushes and terminals of said registers, means for controlling the setting of switches of another type by transmitting impulses thereto under the control of other brushes and terminals of said registers, means dependent upon the office designation of a call for selecting either of said switch controlling means, and means controlled by said last means to select the proper brushes and terminals of said registers.
3. In a telephone exchange system, a switch controlling mechanism, means for

controlling the setting of switches of one type by impulses received from said switches during the setting thereof, means for controlling the setting of switches of another type by transmitting impulses thereto, separate means for determining the number of impulses for the setting of each type of switch, and means operated in accordance with the designation of a call to select the proper number determining means.

4. In a telephone system, a switch controlling mechanism comprising registers having a plurality of elements, means for controlling the setting of switches of one type by impulses received from said switches during the setting thereof under the control of certain elements of said registers and a number determining means, means for controlling the setting of switches of another type by transmitting impulses thereto under the control of other elements of said registers and another number determining means, means operated in accordance with the office designation of a call for selecting one of said number determining means, and means controlled by said last mentioned means to associate the proper elements of said register with said controlling means.

5. In a telephone system, selector switches having directive and trunk hunting movements, a switch controlling mechanism comprising a plurality of registers, an impulse transmitter, means for repeatedly operating said transmitter to transmit series of selector directive impulses under control of said registers, a timing switch, means to operate said switch to introduce a measured interval between successive operations of said impulse transmitter for permitting the trunk hunting movements of said selector switches, and means for at will varying the interval so measured.

6. In a telephone system, selector switches having directive and trunk hunting movements, a switch controlling mechanism comprising a plurality of registers, an impulse transmitter, means for repeatedly operating said transmitter to transmit series of selector directive impulses under control of said registers, a timing switch having a plurality of positions of rest, means to advance said switch between said positions of rest to introduce a measured interval between successive operations of said impulse transmitter for permitting the trunk hunting movements of said selector switches, and means for at will varying the positions of rest to vary the intervals so measured.

7. In a telephone system, selector switches having directive and trunk hunting movements, a switch controlling mechanism comprising a plurality of registers, an impulse transmitter, means for repeatedly operating said transmitter to transmit series of selector directive impulses under control of said

registers, a multi-position switch, means for rendering certain positions of said switch positions of rest, means to advance said switch between said positions of rest to introduce a measured interval between successive operations of said impulse transmitter for permitting the trunk hunting movements of said selector switches, and means for at will rendering other positions of said switch positions of rest to vary the intervals so measured.

8. In a telephone system, selector switches having directive and trunk hunting movements, a switch controlling mechanism comprising a plurality of register, an impulse transmitter, means for repeatedly operating said transmitter to transmit series of selector directive impulses under control of said registers, a multi-position switch, circuits associated with said switch whereby certain positions of said switch are positions of rest, means to advance said switch between said positions of rest to introduce a measured interval between successive operations of said impulse transmitter for permitting the trunk hunting movements of said selector switches, and means for varying the intervals so measured comprising means for at will varying the association of said circuits with said switch to render other positions of said switch positions of rest.

9. In a telephone system, an impulse transmitter having a plurality of normal positions, means for counting the number of impulses transmitted and means to move said impulse transmitter to one of said normal positions in accordance with the number of impulses transmitted.

10. In a telephone system, an impulse transmitter having a plurality of normal positions separated by transmitting positions, said transmitting positions being less in number than the maximum number of impulses to be transmitted, means for counting the number of impulses transmitted and means to move said impulse transmitter to one of said normal positions in accordance with the number of impulses transmitted.

11. In a telephone system, an impulse transmitter having a plurality of normal positions, means for determining the number of impulses to be transmitted, means for arresting said transmitter in a normal position after a predetermined number of impulses have been transmitted, a plurality of conductors connecting said number determining means and said arresting means, and means for rendering only one of said conductors effective at any one time.

12. In a telephone system, an impulse transmitter having a plurality of normal positions, a register for determining the number of impulses to be transmitted, means for arresting said transmitter in a normal position after a predetermined number of

impulses have been transmitted, a plurality of conductors connecting each position of said register with said arresting means and means for rendering only one of said conductors effective at any one time.

13. In a telephone system, a switch controlling mechanism comprising a plurality of registers, an impulse transmitting switch having a plurality of normal positions, multiple connections extending from the terminal banks of said registers, a plurality of conductors connecting each multiple connection with said transmitting switch and means to render only one of said conductors effective at a time.

14. In a telephone system, a switch controlling mechanism comprising a plurality of registers, an impulse transmitting switch having a plurality of normal positions, multiple connections extending from the terminal banks of said registers, a plurality of conductors connecting each multiple connection with said transmitting switch and means for rendering one of said conductors effective in accordance with the normal position from which said switch is moved.

15. In a telephone system, a switch controlling mechanism comprising a plurality of registers, an impulse transmitting switch having a plurality of normal positions, multiple connections extending from the terminal banks of said registers, a plurality of conductors connecting each multiple connection with said transmitting switch, and means for rendering one of said conductors effective in accordance with the position of the register and the normal position from which said switch is moved.

16. In a telephone system, an impulse transmitter having a plurality of normal positions, means for determining the number of impulses to be transmitted, means for starting said impulse transmitter from any normal position, means for arresting said transmitter in a normal position after a predetermined number of impulses have been transmitted, a plurality of conductors connecting said number determining means and said arresting means, and means for rendering said conductors effective in accordance with the normal position from which said switch is started.

17. In a telephone system, a switch controlling mechanism comprising a plurality of registers, an impulse transmitting switch having a plurality of normal positions, multiple connections extending from said registers to said impulse transmitting switch, and means whereby said switch is enabled to pick up said multiple connections in the same numerical order regardless of the normal position from which said switch is moved.

18. In a telephone system, a switch controlling mechanism comprising a plu-

- rality of registers, an impulse transmitting switch having a plurality of normal positions, multiple connections extending from terminal banks of said registers to said impulse transmitting switch, and means whereby said switch is enabled to pick up said multiple connections in the same numerical order regardless of the normal position from which said switch is moved.
- 10 19. In a telephone system, a switch controlling mechanism comprising a plurality of registers, an impulse transmitting switch having a plurality of normal positions, multiple connections extending from terminal banks of said registers to said impulse transmitting switch, means to repeatedly operate said impulse transmitting switch, means successively controlled by said registers to stop the transmission of said impulses and to arrest said switch in a subsequent normal position, and means to associate said multiple terminals with said switch in the same numerical order regardless of the normal position from which said switch is moved.
- 15 20. In a telephone system, a switch controlling mechanism comprising a plurality of registers, an impulse transmitting switch having a plurality of normal positions separated by impulse transmitting positions less 30 in number than the maximum number of im-
- pulses to be transmitted, multiple connections extending from terminal banks of said registers to said impulse transmitting switch, and means whereby said switch is enabled to pick up said multiple connections in the same numerical order regardless of the normal position from which said switch is moved.
21. In a telephone system, a switch controlling mechanism comprising a plurality of registers, an impulse transmitting switch having a plurality of normal positions separated by impulse transmitting positions less 40 in number than the maximum number of impulses to be transmitted, multiple connections extending from terminal banks of said registers to said impulse transmitting switch, means to repeatedly operate said impulse transmitting switch, means successively controlled by said registers to stop 45 the transmission of said impulses and to arrest said switch in a subsequent normal position, and means to associate said multiple terminals with said switch in the same numerical order regardless of the normal position from which said switch is moved.

In witness whereof, I hereunto subscribe my name this 24th day of March A. D., 1927.

GEORGE THOMPSON
